6. CREED

FILLING ATTACHMENT FOR GASOLINE TANKS OF AUTOMOBILES

Filed Nov. 9, 1925

OLIVER CREED

say Murray and Gugelten

Attorney

UNITED STATES PATENT OFFICE.

OLIVER CREED, OF CINCINNATI, OHIO.

FILLING ATTACHMENT FOR GASOLINE TANKS OF AUTOMOBILES.

Application filed November 9, 1925. Serial No. 67,783.

This invention relates to improvements in tank fillers and gauges.

Heretofore when attaching a tank filler and gauge to gasoline tanks and the like, it has been necessary to provide a second hole or bore in the tank in order to mount the filler and gauge. This has been objectionable and quite frequently detracts from the appearance of the automobile. Another objection to gauges generally used is that because of their mounting the gasoline and gasoline vapors would find their way intermediate the transparent observation plate and indicating plate and would cloud or fog the glass or indicating plate so that it became difficult, if not impossible, to obtain a reading.

One of the objects of my invention is to provide a device to overcome the above noted objections.

Another object of my invention is to provide a tank filler and gauge that can be readily mounted upon a gasoline tank without in any way changing or modifying the tank.

Another object of my invention is to provide a device that is simple and economical of construction and operation and that may be attached to a standard gasoline tank in the same manner that the gasoline cap itself is secured to the tank.

These and other objects are attained by the means described herein and disclosed in the accompanying drawings, in which:

Fig. 1 is a graphic illustration of the rear of an automobile and tank having mounted thereon a device of my invention.

Fig. 2 is a transverse section of the tank taken on line 2-2 of Fig. 1.

Fig. 3 is a sectional view taken on line 3-3 of Fig. 2.

Fig. 4 is a sectional view taken on line 4-4 of Fig. 2.

Fig. 5 is a sectional view taken on line 5-5 of Fig. 3.

The device of my invention comprises a pipe-like neck 10 having a nozzle of filling port 11 extending at an angle therefrom. Near the lower end of the pipe 10, there is provided a groove 12 in which the halves 13 and 14 of a ring 15 are secured. The ring 15 forms a shoulder against which the inner face of a flange 16, formed on a coupling nut 17, abuts. The coupling nut 17

is provided with internal threads 18 complementary to the threads formed on the neck or filling port 19 of the gasoline tank 20. From this it is obvious that I have provided a device that may be attached to the automobile as it is delivered to the purchaser.

The nozzle or filling port 11 is provided with threads 21 of the same size and pitch as the threads 18 formed on the neck 19 and a cap 22 is provided with complementary threads for closing the nozzle or filling port 11. The cap 22 may be the standard cap furnished by the automobile manufacturer. A finger 23 extends upwardly from the sleeve or pipe 10 and has mounted at its upper end an indicating gauge 24. The gauge 24 comprises an indicating plate 25 having lugs 26 extending upwardly therefrom. A glass or transparent observation window 27 is provided and is spaced from the indicating plate 25 by the lugs 26. A cap 28 having an opening 29 therein is provided for securing the indicating plate 25 and glass 27 in position. This is accomplished by means of screws 30 or the like extending through the cap 28 into the finger 23 and clamping the indicating plate 25 and glass 27 between the flange 31 of the cap 28, and finger 23. The finger 23 is provided with a web or flange 31 having a bore 32 extending therethrough and through which bore a wire or rod 33 reciprocates. The indicating plate 25 is provided with suitable indicia observable through the observation port 29 formed in the cap 28 for indicating the amount of gasoline in the tank. The upper end of the rod or wire 33 is bent at right angles so that an indicating finger 34 is provided.

Interiorly of the sleeve or pipe 10, a shoulder 35 is formed and into which shoulder a tube 36 is secured. The indicating wire or rod 33 extends through the tube 36. It should be noted that this tube 36 is not for the purpose of guiding the wire or rod 33 but simply a guard to protect the wire from injury by contact of any filling device inserted in the mouth of the nozzle while the gasoline tank is being filled. A bracket 37 is secured to the lower end of the tube 36 and extends downwardly. Pivotedly mounted at the lower end of the bracket 37 is an arm 39, as shown at 38. The other end of the arm 39 has mounted on it a float

40 by any suitable means such as cotter pins 41. Intermediate the ends of the arm 39 the indicating wire or rod 33 is pivotally mounted, as shown at 42.

5 It should be noted that the upper end 43 of the web 31 is spaced from the indicating cap 28 as shown at 44. Any gasoline or fumes that may find their way up through tube 36, upon reaching the space 44 would be lost in the atmosphere and would be excluded from the chamber 45 intermediate the glass 27 and indicating plate 25 to cloud or fog the said glass or plate.

15 In mounting the filling attachment and gauge, the coupling nut 17 would first be placed on the sleeve 10 and the split ring 15 then secured in the groove 12 formed in the sleeve. The ring 15 prevents the coupling nut from becoming disassociated from the 20 sleeve. A gasket 47 is provided intermediate the sleeve 10 and neck 19 for forming a tight joint.

25 It should be noted that the indicating finger 34 reciprocates in the chamber 45, the chamber 45 being provided by means of the lugs 26 extending from the indicating plate 25 and the glass 27 which rests upon the lugs 26.

30 What I claim is:

35 1. A filling attachment for gasoline tanks embodying a filling-nozzle adapted to be removably secured in a vertical position over the inlet-opening of the tank and provided with a removable closure for its upper end, and also having its rear wall extended upwardly to form a finger, said rear wall being provided with a vertical opening positioned substantially in alinement with the front face of said finger, the finger being adapted 40 to support an indicator at its upper end, and said vertical opening being adapted to guide a vertically reciprocating fluid-controlled indicator-rod closely adjacent the rear wall of the nozzle.

45 2. A filling attachment for gasoline tanks embodying a filling-nozzle adapted to be removably secured in a vertical position over the inlet-opening of the tank and provided with a removable closure for its upper end, and also having its rear wall extended upwardly to form a finger, said rear wall being provided with a vertical opening positioned substantially in alinement with the front face of said finger, the finger being adapted 50 to support an indicator at its upper end, and said vertical opening being adapted to guide a vertically reciprocating fluid-controlled indicator-rod closely adjacent the rear wall of the nozzle, said filling-nozzle being inclined from a vertical line for a portion of its length to offset its filling mouth from said finger.

60 3. A filling attachment for gasoline tanks embodying a filling-nozzle adapted to be removably secured in a vertical position over

the inlet-opening of the tank and provided with a removable closure for its upper end, and also having its rear wall extended upwardly to form a finger, said rear wall being provided with a vertical opening positioned substantially in alinement with the front face of said finger, the finger being adapted to support an indicator at its upper end, and said vertical opening being adapted to guide a vertically reciprocating fluid-controlled indicator-rod closely adjacent the rear wall of the nozzle, and a guard member in said nozzle at the rear side thereof to protect said indicator-rod from injury by any filling device inserted in the mouth of the nozzle.

65 4. A filling attachment for gasoline tanks embodying a filling-nozzle adapted to be removably secured in a vertical position over the inlet-opening of the tank and provided with a removable closure for its upper end, and also having its rear wall extended upwardly to form a finger, said rear wall being provided with a vertical opening positioned substantially in alinement with the front face of said finger, the finger being adapted to support an indicator at its upper end, and said vertical opening being adapted to guide a vertically reciprocating fluid-controlled indicator-rod closely adjacent the rear wall of the nozzle, and a guard member in said nozzle at the rear side thereof to protect said indicator-rod from injury by any filling device inserted in the mouth of the nozzle, said guard member being extended below the bottom side of said nozzle so that it will project into the tank and serve as a pivot bearing for the operating means of said indicator-rod.

70 5. A filling attachment for gasoline tanks embodying a filling nozzle having a supporting means for supporting and displaying an indicator to the rear and above the mouth of the nozzle and a guide opening for guiding an indicator-rod in front of said supporting means and closely adjacent to the rear inner face of the nozzle, and a guarding means also located closely adjacent to said rear inner face and spaced therefrom to permit passage of the indicator-rod and 75 to guard said rod from injury by contact of a filling device inserted in the mouth of the nozzle.

75 6. A filling attachment for gasoline tanks embodying a filling nozzle having a supporting means for supporting and displaying an indicator to the rear and above the mouth of the nozzle and a guide opening for guiding an indicator-rod in front of said supporting means and closely adjacent to the rear inner face of the nozzle, and a guarding means also located closely adjacent to said rear inner face and spaced therefrom to permit passage of the indicator-rod and 80 to guard said rod from injury by contact of a filling device inserted in the mouth of the nozzle.

85 130

jury by contact of a filling device inserted in the mouth of the nozzle, said guarding means depending for insertion into a gaso-line tank and co-operating with the walls of the guide opening in the nozzle for protecting said rod remote from the guide opening, said guarding means adapted to pivotally

support a float and float arm within the tank and to which float arm said rod is adapted to be pivotally connected. ¹⁰

In testimony whereof, I have hereunto subscribed my name this 3rd day of November, 1925.

OLIVER CREED.
